US0D1004409S

(12) **United States Design Patent** (10) **Patent No.:** **US D1,004,409 S**
(45) **Date of Patent:** **** Nov. 14, 2023**

(54) **BRACKET**

(71) Applicant: **Clairson, Inc.**, Newark, DE (US)

(72) Inventors: **Jonathan Ralleca**, Rialto, CA (US);
Enrique Beuses, Gilroy, CA (US)

(73) Assignee: **Clairson, Inc.**, Newark, DE (US)

(**) Term: **15 Years**

(21) Appl. No.: **29/746,890**

(22) Filed: **Aug. 18, 2020**

Related U.S. Application Data

(63) Continuation of application No. 16/036,394, filed on Jul. 16, 2018, now Pat. No. 11,470,962, which is a continuation-in-part of application No. 15/683,863, filed on Aug. 23, 2017, now Pat. No. 10,021,974, which is a continuation of application No. 15/434,877, filed on Feb. 16, 2017, now Pat. No. 9,743,762.
